UNITED STATES PATENT OFFICE.

GEORGE DE GEOFRY, OF PARIS, FRANCE,

MAGAZINE-CAMERA.

SPECIFICATION forming part of Letters Patent No. 659,143, dated October 2, 1900.

Application filed March 13, 1900. Serial No. 8,541. (No model.)

To all whom it may concern:

Be it known that I, GEORGE DE GEOFRY, a citizen of the Republic of France, residing at No. 10 Rue Matignon, Paris, France, have 5 invented a new and useful Improvement in Photographic Apparatus, of which the following is a specification, reference being had to the accompanying drawings and to the numerals and letters of reference marked 10 thereon.

My invention relates to a magazine arrangement for photographic apparatus, and has for its object to simplify and render more efficient the adjustment, exposure, and 15 position of the sensitive plates, as hereinafter specified.

In the accompanying drawings, Figure 1 shows, chiefly in horizontal section, a photographic apparatus provided with my invention, the section being taken on the line 1 1 of Fig. 2. Fig. 2 is a transverse section on the line 2 2 of Fig. 1. Fig. 3 is a vertical longitudinal section on the central line of Fig. 1, the section being on the line 3 3 of Fig. 1. 25 Figs. 4 and 5 are details in perspective.

Similar numerals and letters of reference indicate similar parts in the several figures.

The magazine consists of a drawer 1, (shown in perspective in Fig. 4,) in which are placed 30 in the ordinary way metal holders 2, adapted to hold the sensitive plates. The drawer 1 is adapted to be moved to either end of the box 3, which may be said to consist of two compartments X and Y, respectively, the latter 35 being that constituting or containing the dark chamber. If removable, it is provided with a screen or shutter. The box 3 is of such dimensions that besides the necessary space at X in the optical axis of the objective for lodg- 40 ing the plate to be exposed there is sufficient space at Y to also receive the drawer 1. In order to move the drawer 1 into either compartment X or Y, one or more rods 4 are provided fixed to the drawer and united with the 45 cross-bar 5, having a ring 6. The side 7 of the drawer, which forms one of the walls of the dark chamber proper, is of a height equal to the total thickness of all the metal holders 2 less at each end the portion necessary to al- 50 low of the passage of the top and bottom plates. Upon the rear 8 of the box 3 are fixed in the compartment Y one or more flat

springs 9, which press the pile of plates against the opposite or front wall 10. These springs are disposed according to the line of 55 displacement of the drawer, so as not to prevent its movement.

At the forward part of the compartment X, at each side thereof, is secured a hook 11, which hooks when the drawer is moved into 60 the compartment X ride over the top plate-holder and drop behind the edge of said holder when the drawer has reached its extreme limit in the said compartment.

Fixed in the rear wall of the compartment 65 X are horseshoe-magnets 12 12, their poles being flush with the inner surface of said wall. This form of magnet in this relation insures a high degree of efficiency by reason of the juxtaposition of the poles. 70

The several plate-holders 2 having each been charged with a sensitive plate and supposing it is desired to adjust one of the plates for exposure, the box 3 is turned so that the lens 3^a stands in vertical position, and the 75 drawer 1 is then pulled from the compartment Y to that X, and it will be seen that the spring-hooks 11, the flexure and inclined construction of which allow them to be moved upward by contact with the upper holder 2, 80 will catch over the edges 2^a of the plate-holder, as above stated. The drawer having been pulled into the compartment X and immediately pushed back, the holder, with the plate to be exposed, will fall to the bottom of the 85 box 3, be there attracted by the magnets 12, and held firmly in position for exposure. Inclined blocks 13 are provided, as shown particularly in Fig. 1, and it will be observed that as the holder drops it will come in contact with the inclined faces of the blocks 13 and be automatically pushed toward the opposite end of the magazine or box. This provision is necessary because of the thickness 90 of the side 7 of the drawer and results in the 95 proper fastening of the plate for exposure.

In the position of the parts shown in Fig. 1 the top plate has fallen to the bottom of the box and is held there by the magnets, the next succeeding plate occupying the top position of the pile and being ready to be placed in position for the next exposure. The first plate having fallen to the bottom of the apparatus and being kept in position by the 100

action of the magnets upon the metal plate-holder and the drawer being pulled into the compartment X, the spring-catches 14, provided in the side 7 of the drawer, ride over 5 the edges of the holder 2 and engage the edge 2° of the holder held by the magnets, and as the drawer is pushed back the said holder and the plate carried with it ride over the springs 9, the plate becoming the lowest one 10 of the pile, as will be readily understood.

A part of the surface of each of the metal plate-holders is buckled, as shown at 15 in Fig. 5, to assist in holding the plate from movement within the holder, and also to keep 15 the plate from slipping an edge of the holder is slightly turned up, as at 16. (Seen in the same figure.)

In the magazines heretofore in use it was in effect the top plate which was exposed. 20 Then when the drawer was pushed back the exposed plate fell to the bottom of the apparatus, lodging itself under the pile of other plates and becoming the bottom plate when the drawer was put back into the first position 25 for the purpose of presenting another plate for exposure.

According to my invention the upper plate when fallen to the bottom of the apparatus and kept in position by the magnets is the 30 one exposed, and when the drawer is moved into the opposite position the plate just exposed is caught by the catches 14 and brought to its proper place as the lowermost plate of the pile. The next plate to be exposed—that 35 is to say, the then upper one of the pile—takes the exposed position or falls to the bottom of the apparatus at the time the drawer for the purpose of returning the already-exposed plate to the dark chamber has been brought 40 to the end of its backward motion. When the magazine is moved over the exposed plate and the drawer with it, the holder of the just-exposed plate slides from the poles of the magnets, and it is well known that under these 45 conditions there is no appreciable resistance and that the power of the magnets is not impaired. As shown in Fig. 1, the front 10 of the compartment Y is adapted to slide as a lid to permit of the charging of the magazine 50 and is secured by a suitable catch 10°.

It will be seen that my invention diminishes the thickness of the apparatus to that of merely the pile of the plate-holders, which permits of reduction in the length of the bellows or in the size of the apparatus if it contains a capacity of fixed dimensions in place of the bellows.

The general arrangement of the parts of the apparatus not entering into my invention 55 is not essential, my improvement relating more specifically to the constructions and

combinations entering into the magazine. The bulk of the apparatus may be still further decreased by making the magazine telescopic or otherwise collapsible in its character, so 65 that the compartment X may be fitted into or over the compartment Y, or vice versa, while the apparatus is not in use.

It will be seen from the foregoing that my invention provides a drawer-magazine for 70 photographic apparatus, having the plate-holders made of metal arranged so as to expose not the front or top plate brought into the focus of the objective, but that plate when it has fallen to the bottom of the apparatus, 75 the plate being kept in position by magnets acting on the metal holders, and, furthermore, that the magazine having been pushed back from its place in that compartment where the image is taken the focus is consequently not 80 on a level with the plate farthest from the objective, but on a level with the opposite end plate.

My invention is capable of minor changes in construction and arrangement without departing from the spirit thereof. Such changes or departures from the construction herein described as may suggest themselves to the skilled mechanic without the exercise of invention I claim as within the scope of my improvement. 85

Having thus described my invention, I claim—

In a photographic apparatus, the combination of a box having a dark chamber end or 90 compartment Y and an opposite compartment X having hooks 11, a drawer for carrying a pile of spring-held plate-holders and sensitive plates, said drawer being adapted to be moved from one compartment to the other, spring- 95 catches 14 mounted in said drawer, inclined blocks 13 in the compartment X, and magnets 12 in the same compartment; the construction and operation being such that, as the drawer is pulled from the dark chamber, the hooks 100 11 will catch over the top plate-holder and draw it into the compartment X, when it with its plate will fall to the bottom of the apparatus, be slid along by the inclined blocks 13, and attracted and held by the magnets 12 during 105 exposure, to be afterward transferred by the return movement of the drawer, through the medium of the spring-catches 14, to the dark chamber Y and to the bottom of the pile, substantially as set forth. 110

In testimony whereof I hereunto set my hand and seal.

GEORGE DE GEOFRY. [L. S.]
